United States Patent Office

Des. 227,081
Patented June 5, 1973

227,081

PACKAGING CONTAINER

James Alexander, Belleville, N.J., assignor to Scandia
Packaging Machinery Company, Clifton, N.J.

Filed Feb. 9, 1971, Ser. No. 114,100

Term of patent 14 years

Int. Cl. D9—03

U.S. Cl. D9—191

FIG. 1

FIG. 2

FIG. 3

FIG. 5

FIG. 1 is a perspective view of a packaging container showing my new design;

FIG. 2 is a side elevational view;

FIG. 3 is a rear elevational view;

FIG. 4 is a top plan view; and

FIG. 5 is a bottom plan view thereof.

I claim:

The ornamental design for a packaging container, as shown.
